UNITED STATES PATENT OFFICE.

HARRY P. STEVENS, OF NEW YORK, N. Y.

WINDOW-CONTROLLING DEVICE.

Application filed May 20, 1924. Serial No. 714,624.

To all whom it may concern:

Be it known that I, HARRY P. STEVENS, a citizen of the United States, residing in the borough of Manhattan, city, county, and State of New York, have invented certain new and useful Improvements in Window-Controlling Devices, of which the following is a full, clear, concise, and exact description.

Briefly stated, my invention relates to improved apparatus for raising and lowering and adjusting the position of movable panels, such as sash or glass windows of various enclosures, particularly glass windows for automobile bodies and doors. My invention comprises a novel arrangement of parts whereby a window or similar device may be raised and lowered or adjusted in position with greater ease than heretofore while at the same time the parts may be manufactured more economically and the construction over similar devices heretofore used, is simplified and made more efficient in action.

The particular object of my invention is to produce a device of the kind above referred to which shall have a positive and durable clutch mechanism for maintaining the window in the desired position positively and without any tendency to slip or rattle. A further object of my invention is to provide such construction that the parts of the window controlling device may be made easily accessible, if necessary, for adjustment without removing but a small portion of the interior finishings of the enclosure or automobile body or door. A further object of the invention is to provide such construction that the parts may be made in a standard form and yet be applicable to various forms or bodies on which the operating handle may be positioned in the most desirable location without changing the construction to adapt the device to the different requirements. In other words, I have devised a substantially standard universal form of window controlling means which may be installed under varying conditions and requirements without special design and without changing the constructional details.

For a detailed description of one form of my invention which I at present deem preferable, reference may be had to the following specification and to the accompanying

drawings forming a part thereof in which Figure 1 is an interior elevation of the substantial parts of an automobile door having my improved window controlling device applied thereto. Fig. 2 is a cutaway portion 60 of the cover plate showing the operating parts in elevation. Fig. 3 is a transverse sectional view of the spindle and handle attached thereto for operating the parts shown in Fig. 2. Fig. 4 is an inner end view of the 65 bushing or bearing in which the spring for the operating handle is mounted. Fig. 5 is a cutaway view showing the operating portions of Fig. 2 in elevation from the rear. Fig. 6 is a horizontal sectional view taken 70 substantially on the line VI—VI of Fig. 5. Fig. 7 is a transverse sectional view taken on the line VII—VII of Fig. 5 showing the means for attaching the sprocket chain to the window sash or glass. Fig. 8 is a vertical sectional view taken substantially on the line VIII—VIII of Fig. 2. Fig. 9 is a plan view of the locking member for the sprocket wheel.

Referring to the drawings, the numeral 1 80 indicates the frame in which the glass window 2 of an automobile door, body, or similar structure is adapted to slide vertically. The numeral 3 indicates a sprocket chain attached to the lower margin of the glass window or sash by means of a U-shaped metallic binding strip 4 which carries on its lower surface bracket plate 5 which is clamped between two horizontally extending plates 6 and 7 (Fig. 7) by means of two 85 set screws 8 and 9. The last pivot pin 10 of the sprocket chain 3 extends into the clamping plate 7 thereby attaching the chain 3 operatively to the glass panel 2.

The sprocket chain 3 comprises central 90 connecting links 11 of the usual form and outer side plates or links 12 which are formed as indicated in the drawings so that the chain may be flexed in one direction only but will be incapable of being flexed 100 in the opposite direction. This is accomplished by forming abutting end surfaces 13 and 14 on the end of each of the side plates 12, said surfaces being inclined in opposite directions on the two opposite 105 sides of the chain as indicated. This construction not only prevents the chain from being flexed in but one direction but also prevents the links of the chain from slipping or being displaced transversely so that 110

when the links are brought into alignment the outer or straight edges of the chain will form practically continuous surfaces.

The sprocket chain 3 is adapted to pass over the operating sprocket wheel 15 and to be wound upon the cylindrical surface of the counter-balancing drum or casing 16. In view of the fact that the upper end of the chain 3 does not pass below the sprocket wheel 15, the terminal links at the upper end thereof may be of the usual form as indicated at 17.

Referring now to Figs. 2, 3, 4, and 5, the means for turning the sprocket wheel 15 will be described together with a description of the means for allowing the operating handle to be located in various positions. The numeral 18 indicates the operating handle. This handle engages a spindle 19 which carries on its inner end a gear or pinion 20. This spindle is adapted to turn in a bearing 21 having a circular flange or plate 22 adapted to rest on the outer surface of the cover plate 23 of the mechanism. The cover plate 23 is provided with a plurality of holes or openings 24 substantially of the shape indicated in Figs. 1 and 2. The inner end of the bearing 21 is provided with a circular plate 25 and two oppositely disposed flanges 26 extending from diametrically opposite portions thereof for approximately one-quarter of the circumference of the plate on each side, thereby forming a groove adapted to engage the edges of the openings in the cover plate 23 as indicated in Fig. 3, said edges of the cover plate being slightly smaller in diameter than the quadrants at right angles thereto as indicated in Fig. 2. This construction permits the circular plate 25 to be inserted in the openings 24 and then turned 90° so as to hold said plate and bushing 21 in operating position. The openings 24 are provided with extensions 27 forming between them a tongue 28 which is adapted to engage semi-circular notches 29 in the edge of the circular plate 25. When said plate is inserted in one of the openings 24, said tongue 28 will be sprung inwardly until said plate 25 is turned to its final position whereupon said tongue will spring into one of the notches 29 thereby preventing further rotation of said plate 25 or the bushing 21. Small holes 30 are provided in the plate 22 and the cover plate 23 to permit the insertion of a small rod or similar instrument to force the tongue 28 inwardly to disengage it from the notches 29, if it is desired to remove the bushing 21 from the openings.

The pinion 20 is adapted to engage a gear 31 mounted on the central bearing pin 32. The gear 31 engages a similar gear 33 mounted to rotate on the bearing 34. The gear 33 has attached to its inner side by suitable connecting devices such as pins or rivets 35, approximately rectangular locking

plate 36. Obviously, if preferred, the locking plate 36 may be made integral with the gear 33, but I prefer to make the same respectively of die-cut plates for ease of manufacture. The rectangular plate 36 is provided with two counter-sunk holes 37 and is provided with two recesses or openings 38 (Fig. 9), in which the respective ends of a U-shaped spring 39 are retained. This spring passes through the square head of a pin 40, the cylindrical portion of which enters a hole in the sprocket wheel 15. Said spring 39 is slidable in the head of said pin 40. On the opposite side of the sprocket wheel 15 is a circular plate 41 having a series of counter-sunk holes therein as indicated at 42, and as shown in dotted lines in Fig. 2. This plate is rigidly attached to the outer cover plate 43 carried by the inner cover plate and supported therefrom by means of the spacing pins 44 and 45. The gear 15 is also provided with a transverse hole 46 within which is located a preferably steel ball 47. This ball forms a locking element which maintains the sprocket 15 rigidly in position when the handle of the window operating device is not being moved, for the reason that when the parts are in the position illustrated in Fig. 6, the ball 47 will be forced, by the action of the spring 39 on the pin 40 and the gear 33, to ride on the rib or dividing wall between the countersunk holes 37. This action will force the ball 47 into one of the counter-sunk holes or recesses 42 in the fixed plate 41 and, therefore, any pull or thrust on this sprocket chain 3 will not move the sprocket wheel because the same is locked to the plate 41.

When it is desired to raise or lower the window, the handle 18 will be turned toward the right or left as shown in Fig. 1. Upon movement in either one of these directions, the gears 20, 31 and 33 will be rotated correspondingly, and the plate 36 carried by the gear 33 will also be rotated. This motion will cause one of the projections 48 or 48', carried by said plate 36, to engage the pin 40 and bring one of the countersunk recesses 37 into alignment with one of the countersunk recesses 42. The ball 47 will therefore be capable of moving upward from the position illustrated in Fig. 6 thereby disengaging the gear 15 from the plate 41. Further movement of the gear 33 and plate 36 will, by reason of the engagement between the head of the pin 40 and one of the projections 48 or 48', cause the sprocket wheel 15 to rotate as long as the handle 18 is further turned, thus raising or lowering the sprocket chain and consequently the window.

The sprocket chain 3 engages a fixed plate 49 on its outer side as indicated in Figs. 2, 5, and 6. This plate forms a stop which prevents the chain from bending toward the

right from the position shown in Fig. 2, or toward the left from the position shown in Fig. 5, the construction of the links as above referred to preventing movements in the opposite directions from the positions shown in these figures respectively. It will be apparent that the chain 3 where it extends below the sprocket wheel 15 is capable of receiving a thrust from said sprocket wheel without buckling or flexing by reason of the shape of the ends of the side links and the contact with the guide plate 49. Therefore, if the friction of the window sash or glass in its frame is not overcome by the weight of the sash, the sprocket wheel and chain will positively force the window downward.

The end of the sprocket chain 17 is attached to the drum casing 16 by means of a small hook 50, or other suitable device and this casing contains a counter-balancing spiral spring 51, the outer end of which is suitably attached to the casing 50, and the inner end to the transverse pin 52 which carries a square or irregular portion 53 which the inner end of the spring engages by being bent around the same. The pin 52 is provided on its outer end with a slightly reduced portion 54 which is provided with two rectangular grooves at right angles to each other as indicated in Fig. 5, said grooves being adapted to receive a square rod or pin 55, the ends of which will engage recesses on opposite sides of the opening in the plate 43 through which the end of the bearing pin 52 passes. This arrangement provides means for holding said bearing pin 52 in a fixed position which position may be adjusted according to the tension desired to be placed upon the spiral spring 51. Obviously the tension of this spring should be such that the weight of the window glass and attached parts is substantially counter-balanced when the window is half raised or lowered to its mid-position.

From the above description it will be apparent that I have produced an exceedingly simple, durable, and positively operating window controlling device. It should be noted that the openings 24 are so arranged that the handle and gear 20 may be located in any one thereof, and in each of said positions the pinion 20 will engage either the gear 31 or the gear 33. If the sprocket chain and its connection with the window glass or sash is located substantially in the middle of the lower edge of the latter, as is usually the case, the operating plates for the mechanism may be located relative thereto as shown in Fig. 2, or if desired, the positions of the parts may be reversed so that the chain 3 will be toward the left hand ends of said plates instead of the right hand as indicated in Fig. 2. This fact therefore provides seven different positions in which the handle may be located depending upon the

size of the door or window and upon whether the hinges are on the right or left hand side of the door. Obviously if the handle be placed in the opening at the right of Fig. 2, the handle will be substantially in the middle of the door, and may be made exactly so, if desired, by adjusting the position of the plates 23 and 43 to bring this about. Thus the whole mechanism may be standardized and yet will be practically of universal adaptation to different locations without changes in design or shape of the parts. Other advantages thereof will be obvious to those skilled in the art.

Having thus described this form of my invention, I do not wish to be understood as being limited to the details of form and specific arrangement of parts set forth, for various changes may be made by those skilled in the art without departing from the spirit and scope of my invention as set forth in the appended claims.

What I claim and desire to protect by Letters Patent is:

1. In a controlling mechanism for a window or the like, a suitable housing therefor comprising a cover plate on one side thereof, raising and lowering mechanism located within said housing, said cover plate having a plurality of openings, a bearing member adapted to be retained in any one of said openings, and an operating member which is adapted to be supported in said bearing member and engage said mechanism.

2. In a controlling mechanism for a window or the like, a suitable housing therefor comprising a cover plate on one side thereof, raising and lowering mechanism located within said housing, said cover plate having a plurality of openings therein located in substantially horizontal alignment, a bearing member adapted to be locked in any one of said openings, and a manually operated handle or part which is adapted to be supported in said bearing member and engage said mechanism.

3. In a controlling mechanism for a window or the like, a suitable housing therefor comprising a cover plate on one side thereof, raising and lowering mechanism located within said housing, said cover plate having a plurality of openings therein located in substantially horizontal alignment, a manually operated handle or part, a driving member carried thereby and which is adapted to engage said mechanism when placed in any one of said openings, a bearing member for said parts, and a spring for locking said bearing in operative position in said cover plate when placed in any one of said openings.

4. In a controlling mechanism, for a window or the like, in combination, a supporting plate having an opening therein to receive an operating member, the margins of said

plate about said opening carrying a flexible part projecting therefrom, a bearing adapted to be inserted in said opening and having a portion adapted to engage said flexible part to lock said bearing in position, and an operating member adapted to be carried by said bearing member.

5. In a controlling mechanism, for a window or the like, in combination, a supporting plate having an opening therein to receive an operating member, the margin of said opening being formed with a flexible projection extending therefrom, a bearing adapted to be inserted in said opening and having a recess adapted to engage said projection to lock said bearing in position, and an operating member carried by said bearing.

6. In a controlling mechanism, for a window or the like, in combination, a supporting plate having an opening therein to receive an operating member, the margin of said opening being formed with a flexible projection extending therefrom and annular cut-away portions on opposite margins thereof, a bearing member having a portion adapted to engage said projection to lock said bearing member in position and having oppositely disposed annular flanges adapted to enter said annular cut-away portions and to engage said plate between the same when said bearing member is rotated, and an operating member carried by said bearing member.

35. 7. In a controlling mechanism for a window or the like, a suitable housing comprising a cover plate on one side thereof, raising and lowering mechanism located within said housing, said cover plate having a plurality of elongated openings the margins of said openings being shaped at one end to form a spring member or tongue projecting inwardly, and a manually operated handle or part adapted to engage said mechanism when placed in any one of said openings having an elongated member adapted to pass through said openings in one position, and to be retained therein when rotated to an-

other position, said latter member having a groove on its edge adapted to receive said tongue when in the latter position.

8. In a controlling mechanism for a window or the like, a suitable housing comprising a cover plate on one side thereof, raising and lowering mechanism located within said housing, said cover plate having a plurality of circular openings therein, the edges of each of said openings being cut away to form an inwardly projecting tongue, and a manually operated handle or part adapted to engage said mechanism when placed in any one of said openings, and a circular plate having two oppositely disposed flanges adapted to pass through said circular openings and to engage the edges thereof when rotated, said circular plate having a groove on its edge located intermediate said flanges adapted to receive said tongue when said flanges engage the edges of said openings.

9. In a controlling mechanism for a window or the like, a suitable housing comprising a cover plate on one side thereof, raising and lowering mechanism located within said housing, said plate having a plurality of similar openings shaped with an inwardly projecting tongue, and a manually operated part adapted to engage said mechanism when placed in any one of said openings comprising a bearing having a flange adapted to rest on the outer surface of said cover plate, a spindle in said bearing having a pinion on its inner end for engaging said mechanism, and a handle on its outer end, and a plate member on the inner end of said bearing having oppositely disposed flanges and a groove on its edge intermediate said flanges adapted to receive said tongue, whereby said manually operated part may be inserted in any one of said openings and locked therein when rotated with said flanges engaging the edge of the opening and said tongue engaging said groove, and means for releasing said tongue from said groove.

HARRY P. STEVENS.
